CHEST OF DRAWERS

Frank P. Mitten, Redlands, Calif.

Application September 10, 1949, Serial No. 115,042

1 Claim. (Cl. 312—270)

1

This invention relates to storage cabinets or chests of drawers and more particularly to chests of the type having a plurality of drawers for the storage of small articles requiring a large number of relatively shallow drawers.

The objects of the invention are to provide a cabinet or chest of drawers which is economically constructed from a minimum of parts, which is easily and quickly assembled, and in which the drawers are substantially dust-proof so as to maintain the contents thereof in clean condition.

The invention will best be understood from the following description of the present preferred embodiment thereof, taken in conjunction with the drawing, in which,

Fig. 1 is a perspective view of a completed cabinet;

Fig. 2 is a partial perspective view of the rear end of a cabinet showing the back panel partly broken away and one of the separators slightly withdrawn;

Fig. 3 is a detailed fragmentary side elevation taken on the line 3—3 of Fig. 1;

Fig. 4 is a perspective view of a single drawer;

Fig. 5 is a sectional view through the front portion of the cabinet showing the rear end of one of the drawers in its relation to the front end of one of the separators;

Fig. 6 is a broken side elevation of one of the separators as shown in Fig. 3;

Fig. 7 is a similar view of a modified form of separator;

Fig. 8 is a front elevation detail showing the junction of one separator with a side panel; and

Fig. 9 is a side elevation showing another form of separator front edge formation.

Referring to Figs. 1 and 2, the chest of drawers comprises four principal elements, a rectangular wooden casing open at front and back consisting of side panels 10 and 11, a top panel 12 and a bottom panel 14; a set of sheet metal separators 15; a set of drawers 16; and a back panel 18.

The side panels 10 and 11 are provided adjacent their top and bottom edges with grooves 19 to receive the tongues 20 on the top and bottom panels, these four panels preferably being made of ply-wood of suitable thickness, for example, about 1 1/4" thick, and being glued together at their jointed edges.

The side panels are also provided on their opposed inner surfaces with spaced apart horizontally aligned grooves 21 which extend straight through from front to back, the first groove at the top being placed immediately underneath the bottom surface of the top panel 12 and the last

groove at the bottom spaced from the bottom panel by the depth of one drawer.

The separators are formed from sheet metal which is flat except at its rear end where it is provided with a downwardly turned flange 22 which forms a right angle with the body 24 and is co-extensive with the width of said body portion. The forward edge of the separator is folded over on itself throughout its width, preferably twice as shown at 25 in Fig. 6, and, if desired, a greater number of times for increased strength as shown at 26 in Fig. 7. Immediately underlying the forward folded edge of the separators they are provided with a forwardly extending lip 28 which may be a part of a sheet metal strip which is twice bent at right angles throughout its length, first downwardly at 29 and then forwardly at 30, the rear portion 31 of said strip being spot welded to the underside of the body 24 of the separator. Alternatively, the lip may be formed by folding the material of the separator forwardly after it is bent back on itself. Fig. 9 shows such a construction in which the lip 28' is formed from the doubled over front edge of the separator sheet 24, making a very rigid edge structure.

The grooves 21 in the side walls are of just sufficient width to receive the folded edge portion 25 or 26 so that the separators may be inserted in the assembled wooden cabinet from the rear. The length of the separators is such that when the rear flange 22 engages the rear faces of the side walls 10 and 11, the forward edge of the separator is in alignment with the forward edges of the cabinet.

Each drawer 16 is made from a single sheet of metal with a flat bottom 34, upturned side walls 35 and 36, rear wall 38 and front wall 39. The front wall is provided at its top edge with an inwardly turned tongue 40 which is so dimensioned as substantially to fill the space between the front end 25 of the separator and the lip 28 attached thereto or formed thereon.

The strip of metal of which the lip 28 is a part 45 is of such length as to enter freely between the side walls 35 and 36 of the drawers, and is therefore somewhat narrower than the body 24 of the separators, as may be seen in Fig. 8, and the tongue 40 which extends rearwardly parallel to the bottom 34 of the drawer is approximately in alignment with the top edges of its side walls. The separators are so spaced in the cabinet relative to the depth of the drawers that the top edges of the side and rear walls of the drawers 50 are spaced from the overlying separators by the

thickness of the sheet metal strip 31. The relative thickness dimensions of all of these sheet metal parts are greatly exaggerated in the drawings for the sake of clarity, which makes the clearances appear larger than they are in actual practice.

The assembly of wooden cabinet and sheet metal separators is held together after insertion of the separators by application of the rear panel 18 which is screwed tightly to the rear faces of the side, top and bottom walls, and locks the separators in place by engagement with the rear flanges 22. The thickness of the latter flanges is so slight in actual practice that the back panel may be pulled into contact with the rear faces of the cabinet around its edges, forming a dust-proof joint. The flat drawer bottoms slide freely on the upper surfaces of the separators and the upper front and rear edges of each drawer are sealed in a dust-proof manner by reason of the overlapping relation of the tongues 40 and the lips 28 and the overhanging of the drawers at the back by the flanges 22.

Referring to Fig. 5, it will be noted that when a drawer is pulled nearly all the way out, its rear wall 38 engages the vertical portion of the sheet metal member which provides the lip 28, as shown in full lines in Fig. 5. In this position, the drawer bottom rests against the folded reinforced edge 25 of the separator. To remove the drawers completely it is necessary only to lift their front ends to tilt the drawer to the dotted line position of Fig. 5 so that the rear wall is disengaged from said sheet metal member.

While the invention has been described by reference to the details of the illustrative embodiment, it is to be understood that it is not limited thereto but is to be construed broadly within the purview of the claim.

What is claimed is:

A chest of drawers comprising a rectangular wooden frame having sidewalls of substantial thickness and a top and a bottom, said sidewalls having spaced apart alined grooves cut in their opposed inside surfaces and extending parallel to said top, sheet-metal separators extending across

said frame and slidably positioned in said grooves, each separator having a rear flange coextensive with the width of the separator downwardly turned at a right angle and overlying at its ends a portion of the rear face of each sidewall, a rear panel secured to said frame and overlying said rear flanges thereby locking said separators in place, the front of each separator being folded over on itself throughout its length to form a reinforced front edge, said grooves having a width sufficient to slidably receive said folded front edge, a forwardly extending sheet-metal lip underlying and spaced from said front edge on the under side of each separator and shorter than the space between said side walls so as to permit sliding of said separators in said grooves, sheet-metal drawers of a size substantially to fill the spaces in said frame between said separators, said sheet-metal lips corresponding in length to the inside width of said drawers, each drawer having at its upper front edge an inwardly extending sheet-metal tongue adapted to enter the space between the lip and the front edge of the overlying separator, said drawers being of such length that when fully closed their rear walls engage said rear flanges and their tongues are seated in the spaces between the lips and the reinforced edges of the separators.
